(57) **CLAIM**

The ornamental design for a loose leaf binder, as shown and described.

DESCRIPTION

FIG. 1 is a front view of the loose leaf binder;

1 Claim, 7 Drawing Sheets

FIG. 2 is a plan view of the binder;

FIG. 3 is a bottom view of the binder;

FIG. 4 is a right side view of the binder;

FIG. 5 is a left side view of the binder;

FIG. 6 is a cross section taken along the line A—A of FIG. 1;

FIG. 7 is a front view of the loose leaf binder with the rings opened;

FIG. 8 is a plan view of the binder with the rings opened;

FIG. 9 is a bottom view of the binder with the rings opened;

FIG. 10 is a right side view of the binder;

FIG. 11 is a left view of the binder;

FIG. 12 is a cross section taken along the line B—B of FIG. 7;

FIG. 13 is an enlarged partial cross section similar to FIG. 6;

FIG. 14 is an enlarged partial cross section similar to FIG. 12;

FIG. 15 is an enlarged partial cross section taken along the line C—C of FIG. 1, except that the lever is indicated as outer appearance for the sake of clarity;

FIG. 16 is an enlarged partial cross section taken along the line D—D of FIG. 1, except that the lever is indicated as outer appearance for the sake of clarity;

FIG. 17 is a cross section similar to FIG. 15 with the rings are opened;

FIG. 18 is a right end elevational view of a second embodiment of a loose leaf binder showing my new design, the only difference being the lever;

FIG. 19 is a left end elevational view thereof; and,

FIG. 20 is a front elevational view of a third embodiment of a loose leaf binder showing my new design the only difference being the additional ring.
